CLAIM

The ornamental design for a plastic bucket lid removal tool, as shown and described.

DESCRIPTION

FIG. 1 is a side elevation view of a bucket lid removal tool showing my new design;

FIG. 2 is a left end view thereof;

FIG. 3 is a bottom plan view thereof;

FIG. 4 is a top plan view thereof;

FIG. 5 is a handle end view thereof;

FIG. 6 is an opposite second side elevation view thereof; and

FIG. 7 is a side view of a cutting blade mounted in the tool illustrated in FIG. 6; shown separately for clarity of illustration.
